WITNESS:

UNITED STATES PATENT OFFICE.

KUWAKICHI FUJITA, OF HAZLETON, PENNSYLVANIA.

COOLER.

1,383,925.

Specification of Letters Patent.

Patented July 5, 1921.

Application filed June 15, 1920. Serial No. 389,173.

To all whom it may concern:

Be it known that I, KUWAKICHI FUJITA, a subject of the Emperor of Japan, residing at Hazleton, in the county of Luzerne and State of Pennsylvania, have invented new and useful Improvements in Coolers, of which the following is a specification.

This invention relates to coolers and more particularly to cooling devices designed and 10 constructed for employing the cooling effect of water or moisture as it evaporates.

Some of the objects of the invention are: to produce a device of the character mentioned which is designed to insure a temperature considerably lower than that without the device by disturbing the air within the device to facilitate and cause a more thorough evaporation; to produce a device of the character mentioned which embodies apparatus for more effectively saturating a fabric which incloses the storage compartment forming a part of the device. With these and other objects in view the invention resides in the combination, arrangement and 25 operation of parts hereinafter more fully described and illustrated in the accompanying drawings, in which:

Figure 1 is a perspective view of the device embodying the present invention; Fig. 30 2 is a central vertical sectional view; Fig. 3 is a detail view of the means for actuating the liquid spraying device; Fig. 4 is a detail view of the escapement means forming a part of the means for actuating the liquid spraying device.

Generally stated the device consists of a storage compartment 10, a supported fabric 11 which incloses the storage compartment, an apparatus for saturating or spraying the 40 fabric, which apparatus includes a foraminated member 12 and means 13 for rotating the member 12.

Referring now to the drawing, it will be seen that, the storage compartment 10 is 45 formed within the housing or casing 14, which is open at the top and which is also provided with air passages 15 and a door 16. The fabric 11 is supported from a ring 17. The ring 17 is supported by the upper part 50 of a frame 18. The frame 18 serves to hold the fabric 11 in a compartment forming condition. A tank 19 is supported upon the top of the housing 14. The tank 19 is equipped with a drip cock 20.

55 The apparatus for saturating the fabric 11 consists of the member 12 which in the pres-

ent instance is constructed from suitable foraminous material. The member 12 is formed into the shape of a dome and its base is sufficiently large to encircle the fabric 11 as supported by the ring 17. It will be noted 60 that the fabric 11, due to the shape of the frame 18, is spread out and encompasses a much larger area cross-sectionally throughout the major portion of its length. The particular arrangement of the fabric on the frame 18 insures an effective saturation of 65 the fabric. The member 12 is carried by a shaft 21. One end of the shaft 21 is supported on the point of the bearing member 22 at 70 the top of the frame 18, while the upper end of the shaft 21 is held in position by a bearing member 23, as shown in Fig. 3 of the drawing. A spring motor 24, or the like, is utilized for imparting motion to a train of 75 gears 25, which in turn impart motion to a disk 26 mounted for rotation on a shaft 27. The disk 26 is provided with pins 28. The disk 26 forms a part of an escapement means which also includes a disk 29 mounted for 80 movement on a shaft 30. The disk 29 is provided with a V shaped notch 31 and a projection 32, the purpose of which will appear. A gear 33 is mounted on the shaft 30 and said gear 33 meshes with a gear 34 secured to 85 the shaft 21. A flexible element 35 has one end thereof secured to the shaft 21 and the opposite end of said element is attached to one end of a helical spring 36. The free end of the spring 36 is secured to a part of the 90 housing 14.

In operation, the water in the tank 19 is allowed to pass through the drip cock 20, onto the member 12. By virtue of the motor 24 and the intervention of gears motion is 95 transmitted to the disk 26. In the rotation of the disk 26 one of the pins 28 is caused to enter the notch 31. As the disk 26 continues to rotate and inasmuch as the particular pin 28 engages one of the walls of the notch 31, 100 movement of the disk 29 results. As shown the disk 29 moves in a counter-clockwise direction. Through the intervention of shaft 30 and gears 33 and 34, upon movement of the disk 29, movement is imparted to the shaft 105 21, and consequently to the member 12. As the shaft 21 rotates, the element 35 will be wound on the said shaft against the contractual tension of the spring 36. As the disk 26 continues to rotate, the particular pin 28 110 moves out from the notch 31. Immediately the pin leaves the notch, the spring 36 comes

into play and causes the disk 29 to move in a clockwise direction with the result that the projection 32 will encounter another of the pins 28. This latter action causes the water 5 embodied by the member 12 to be positively precipitated against the fabric 11 below. The continued rotation of the member 12 in opposite directions alternately, insures the proper saturation of the fabric 11, and stirs 10 up the air within the compartment 10 as well, thereby augmenting the evaporation of water.

It should be noted that the frame 18 upon 15 which the fabric 11 is supported is of such construction as to provide a reduced upper section and a relatively enlarged lower section. Such disposition of the fabric makes the saturation thereof an achievement easy to obtain, inasmuch as the portion of the 20 fabric at the juncture of the reduced and enlarged sections, presents a broader surface as disposed as against its being disposed vertically.

Provision is made for draining the bottom 25 of the casing whereat the drippings from the fabric accumulate, and to this end therefore, a drip tray 37 is positioned beneath the fabric. The tray is provided with an outlet 38.

30 What is claimed is:

1. A device as characterized comprising a casing embodying a storage compartment and air passages, a fabric inclosing said compartment, and in combination, apparatus for 35 periodically spraying said fabric with a liquid, including a rotatable member which temporarily retains the liquid.

2. A device as characterized comprising a casing embodying a storage compartment and air passages, a fabric inclosing said compartment, and in combination, apparatus 40 for periodically spraying said fabric with a

liquid, including a reversibly rotatable member of foraminated material.

3. A device as characterized comprising a 45 casing embodying a storage compartment and air passages, a fabric inclosing said compartment, and in combination, apparatus for periodically spraying said fabric with a liquid, including a reversibly rotatable fo- 50 raminous member, and means for rotating said member.

4. A device as characterized comprising a casing embodying a storage compartment an 55 air inlet and a water outlet, a fabric inclos- ing said compartment, and in combination, apparatus for periodically spraying said fabric with a liquid, including a rotatable foraminous member, and means for rotating 60 said member in opposite directions alter- nately.

5. A device as characterized comprising a casing in which air may circulate and em- 65 bodying a storage compartment, a fabric in- closing said compartment, and in combina- tion, apparatus for periodically spraying said fabric with a liquid, including a ro- 70 tatable liquid retaining member, means for rotating said member in opposite directions alternately, and means for vibrating said member.

6. A device as characterized comprising a casing in which air may circulate and em- 75 bodying a water outlet and a storage com- partment, a frame, a fabric supported by said frame so as to provide a reduced upper section and a relatively enlarged lower sec- 80 tion, and in combination, apparatus for per- iodically spraying said fabric with a liquid, including a rotatable liquid retaining mem- ber which is arranged above said fabric.

In testimony whereof I have affixed my 85 signature.

KUWAKICHI FUJITA.
